UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 20,635, dated March 24, 1891.

Application filed October 28, 1890. Serial No. 369,619. Term of patent 14 years.

To all whom it may concern:

Be it known that I, GEORGE H. BABCOCK, a citizen of the United States, residing in Plainfield, in the county of Union and State 5 of New Jersey, have invented and produced a new and original Design for Roofing or Sheathing Tiles, of which the following is a specification, reference being had to the accompanying drawings, forming a part thereof.

10 The design relates to a clay or other tile in which the ornamental effects are produced by the outline of a tile by the surface ornamentation thereof and by the conjunction of the two.

15 The design consists of a tile, the outline of its lower sides being formed by a series of corrugations or serrations terminating in an irregular point; and it also consists in the surface ornamentation formed by a border composed 20 of two rope-like strands uniting at the end of the tile in a representation of a knot.

In the accompanying illustrations, Figure 1 illustrates a face view of a tile of the new design; Fig. 2, an edge view thereof; Fig. 3, a 25 cross-section of the same on the line 3 3 of Fig. 1.

The design relates particularly to the exposed or lower face of a tile, the upper portion partaking of various shapes.

30 As illustrated, the tile is substantially of diamond form, the two upper sides bearing upper flanges *a b*, and the two lower sides *c d*

are made up of a series of small corrugations or serrations which terminate at the lower end of a serrated convex curve *e*, a serrated downward projection *f*, and a serrated lateral projection *g* with rounded ends.

The surface *i* of the tile is substantially flat. The two lower sides are formed with a border of bead form, the surface of which is 40 composed of a number of serrations transversely connected and having the appearance of two strands of rope in conventional form. These two beaded borders unite at the lower end of the tile in the representation of a knot 45 *h*, which are likewise serrated, as are the beaded borders. Two portions of the knot are raised above the surface of the beaded border, and one of these portions is raised above the other, as shown. It may be stated that when a number 50 of tiles of like ornamentation are associated together in use they present a surface resembling net-work.

What is claimed is—

The design for a tile, substantially as described and shown.

In witness whereof I have hereunto set my hand this 2d day of October, A. D. 1890, in presence of two witnesses:

GEO. H. BABCOCK.

Witnesses:

CHAS. W. FORBES,
GEO. H. GRAHAM.
